CONTAINER CLOSURE WITH APPLICATOR ROD AND METHOD OF MAKING THE SAME

William F. Schmalz, Rockville, Conn., assignor to Colt's Patent Fire Arms Manufacturing Company, Hartford, Conn., a corporation of Connecticut

Application August 25, 1939, Serial No. 291,864

10 Claims. (Cl. 15—140.3)

The invention relates to a combined container closure and applicator rod, and more particularly to a container closure and applicator rod which are both of rigid construction such as may be formed by molding a material of the synthetic resin class.

The primary object of the invention is to provide a combined container closure and applicator rod such that the parts thereof may be preformed to final shape prior to assembly and yet may be easily assembled in a positively interlocked relationship.

Another object is to provide a container closure and applicator rod of the above character in which at least the applicator rod is formed from a material of the synthetic resin class.

A further object of the invention is to provide a method of making a combined closure and applicator rod of the above character.

From the following description further objects and advantages of the invention will be apparent to those skilled in the art.

In the accompanying drawing I have shown two alternative embodiments of the invention, but it will be understood that the drawing is intended for illustrative purposes only and is not to be construed as defining or limiting the scope of the invention, the claims forming a part of this specification being relied upon for that purpose.

In the drawing:

Fig. 1 is an elevational view of a bottle provided with a combined closure and applicator rod incorporating the principles of the invention.

Fig. 2 is a sectional view of the closure and applicator rod shown in Fig. 1.

Fig. 3 is an enlarged fragmentary sectional view showing, in elevation and before assembly, the detailed construction for holding the closure and applicator rod together.

Fig. 4 is a view similar to Fig. 3 but showing the closure and applicator rod assembled.

Fig. 5 is a sectional view taken on the line 5—5 of Fig. 4.

Figs. 6 and 7 are views similar to Figs. 3 and 4, respectively, showing an alternative construction incorporating the principles of the invention.

Prior to this invention it has been usual to provide rigid container closures with applicator rods made of glass; however, many difficulties have been attendant upon the use of such rods. Among the troubles experienced have been damage to the container closure if the assembly was effected while the glass was in a fused (plastic) condition, breakage of both closures and rods during assembly, insecure connection between rods

and closures, and the necessity for expensive shipping cartons to prevent rod breakage during transit. The present invention overcomes these objectionable features.

5 In accordance with the invention a preformed container closure member and a preformed applicator rod member are provided, one of these members having a rigid walled recessed formed therein and the other member having a portion thereof positioned and secured within the said recess so that the members are normally inseparable. By "preformed" is meant that the member is shaped to final form prior to its assembly with the other member and by "normally inseparable" it is meant that the members are positively secured against separation unless sufficient force is applied to produce a distortion of some part of the assemblage to thus overcome the positive securing.

10 Referring to Fig. 1, 1 represents a bottle or container of any desired form which is adapted to hold a liquid. At 2 is shown a container closure member having a sealing gasket 3 positioned therein. An applicator rod member 4 is secured 15 to the closure member and the rod is preferably provided at its lower end with a globular applicating portion 5.

15 Figs. 2, 3, 4 and 5 more particularly illustrate 30 one embodiment for positively securing the rod and closure members together. In the illustrated construction the closure member 2 which is preformed of any desired rigid material, preferably being molded from a material of the synthetic resin class, is provided with a screw thread 6 for 35 securing it to the container 1. A cylindrical flange 7 projects downward from the inner surface of the closure, thus forming a recess 8 therein. The side wall of the recess 8 is shouldered, preformed means such as one or more integral 40 ribs 9 projecting into the recess from the side wall thereof, being provided for this purpose. These ribs may be of any desired cross sectional shape, but when the closure is a molded one having the screw thread 6 the ribs are preferably 45 shaped as shown on an enlarged and exaggerated scale in Fig. 3. In actuality these ribs are preferably about .002 to .003 of an inch in height so that as the closure is unscrewed from the mold the ribs are stripped from the mold without being 50 damaged.

When the closure member is formed as described, the upper end portion of the applicator rod member 4, which is preferably molded from a material of the synthetic resin class which is more resistant to chemical action and moisture

absorption than the material from which the closure member is formed, is provided with an enlargement or shouldering means in the form of one or more preformed integral ribs 10. These ribs are preferably shaped as shown.

The closure and rod members are assembled by merely placing the ribbed end of the rod in the recess and then forcing the ribs 10 inward beyond the ribs 9. This may be done while the members are at substantially the same temperature and while in a non-plastic condition, and this without breakage due to the slight inherent resilience of the members.

In order to substantially prevent any relative pivotal movement between the closure 2 and rod 4, one of these members is provided with one or more projections, such as shown at 11, which engage the other member.

While the now preferred embodiment is shown in Figs. 2, 3, 4 and 5, the principles of the invention may be incorporated in constructions quite different in detail, and Figs. 6 and 7 illustrate, by way of example, one such alternative construction. Referring now to Figs. 6 and 7, a container closure is shown at 2^a. The closure is provided with a thread 6^a and a cylindrical flange 7^a forming a recess 8^a. The side wall of the recess 8^a is provided with preformed shouldering means in the form of a thread 9^a and nib 9^b. The lead of the thread 9^a is preferably the same as that of thread 6^a so that the closure, if molded, can be readily unscrewed from the mold without stripping either thread 6^a or 9^a from the mold. The nib 9^b must be stripped from the mold and is, similarly to the ribs 9 shown in Fig. 3, actually about .002 to .003 of an inch in height.

When the container closure is provided with shouldering means such as the thread 9^a and nib 9^b, an applicator rod 4^a is provided which preferably has shouldering means thereon such as shown. The illustrated shouldering means comprises a plurality of preformed integral projections 10^a, 10^b, 10^c, 10^d, and 10^e helically directed to form an interrupted screw thread. The projections 10^a, 10^b, and 10^c are shown in Fig. 6 on the front side of the applicator rod and on the back side of Fig. 7.

The closure 2^a and rod 4^a are assembled by screwing the rod into the recess 8^a, the projection 10^c being forced over and beyond nib 9^b as the rod is fully seated in the recess (Fig. 7). Once assembled, it is apparent that the rod and closure cannot be separated except by applying force thereto sufficient to distort them by forcing 10^c over nib 9^b.

Projections 11^a similar to those shown at 11 in Fig. 3 may be provided if desired to prevent relative pivotal movement of the closure and rod.

Various changes and modifications within the scope of the appended claims will be readily apparent to those skilled in the art.

I claim:

1. In combination, a container closure member molded from a material of the synthetic resin class, and an applicator rod member molded from a material of the synthetic resin class which is more resistant to chemical action and moisture absorption than the material of the closure member secured to said container closure member.

2. In combination, a rigid container closure member, and a rigid applicator rod member, one of said members having a recess therein and the other member having a portion thereof positioned within said recess, said members including inter-

locked preformed cooperating means for positively preventing separation of the members upon relative separative movement thereof in any direction.

3. In combination, a rigid container closure member, and a rigid applicator rod member, one of said members having a recess therein and the other member having a portion thereof positioned within said recess, said members including inter-

locked preformed cooperating means for positively preventing separation of the members upon relative separative movement thereof in any direction and being the sole means for preventing such movement.

4. In combination, a rigid container closure member, and a rigid applicator rod member, one of said members having a recess therein and preformed means projecting into the recess from a side wall thereof, the other member having a portion positioned within said recess and having preformed means thereon cooperatively interlocked with said first named means for positively preventing separation of said members upon relative separative movement thereof in any direction.

5. In combination, a rigid container closure member, and a rigid applicator rod member, one of said members having a recess therein and having preformed means integral with the side wall thereof projecting into said recess, the other member having a portion thereof positioned within said recess and including an integral preformed part cooperatively interlocked with said first named means for positively preventing separation of said members upon relative separative movement thereof in any direction.

6. In combination, a rigid container closure member and a rigid applicator rod member, one of said members having a recess therein and having a preformed rib integral with the sidewall thereof and extending into the recess, the other member having a portion thereof positioned within said recess and having a preformed integral rib thereon cooperatively interlocked with said first-named rib for positively preventing removal of said portion from the said recess.

7. In combination, a rigid container closure member, and a rigid applicator rod member, one of said members having a recess therein and a preformed rib integral with the side wall of and extending into the recess, the other member having a portion thereof positioned within said recess and having a preformed integral rib thereon cooperating with said first named rib to normally prevent removal of said portion from the said recess, one of said members including means spaced from its said rib and engaging the other member to prevent any substantial relative pivotal movement of said members transversely of the longitudinal axis of the applicator rod member.

8. In combination, a container closure molded from a material of the synthetic resin class, said closure having a recess therein and a rib projecting approximately .003 of an inch into said recess from the side wall thereof, and an applicator rod having an end portion positioned in said recess and having a rib thereon cooperatively interlocked with said first named rib for positively preventing separation of the closure and rod upon relative separative movement thereof in any direction.

9. The method of making a combined container closure and applicator rod comprising forming a rigid container closure having a shoul-

dered recess therein, forming an applicator rod with an enlargement adjacent one end, inserting the enlarged end of the applicator rod in said recess while maintaining the closure and rod at substantially the same temperature and in a non-plastic condition, and forcing the enlargement on said rod beyond the shoulder of said recess to assemble the closure and rod with said enlargement cooperatively interlocked with said shoulder for positively preventing separation of the container closure and applicator rod upon relative separative movement thereof in any direction.

10. The method of making a combined container closure and applicator rod comprising 15 molding from a synthetic resin material a rigid

container closure having a shouldered recess therein, forming an applicator rod with an integral enlargement adjacent one end, inserting the enlarged end of the applicator rod in said recess while maintaining the closure and rod at substantially the same temperature and in a non-plastic condition, and forcing the enlargement on said rod beyond the shoulder of said recess to assemble the closure and rod, with said enlargement cooperatively interlocked with said shoulder for positively preventing separation of the container closure and applicator rod upon relative separative movement thereof in any direction.

WILLIAM F. SCHMALZ.
